UNITED STATES PATENT OFFICE.

MURIEL BURKE-HENNESSY, OF NEW ROCHELLE, NEW YORK.

RAZOR-BLADE HOLDER.

Application filed April 28, 1921. Serial No. 465,259.

To all whom it may concern:

Be it known that I, MURIEL BURKE-HENNESSY, a citizen of the United States of America, residing at New Rochelle, in the county of Westchester and State of New York, have invented certain new and useful Improvements in Razor-Blade Holders, of which the following is a full, clear, and exact description.

This invention relates to holders for safety razor blades and has for its principal object to provide a holder whereby such blades may be usefully employed for various purposes after they are no longer useful for shaving.

Safety razor blades, even those of the types which may be stropped, honed and re-ground, have a limited life so far as use in shaving is concerned. It has been customary to discard these blades after their useful application as shaving implements terminated. I have devised means whereby these formerly discarded blades may be employed for a variety of purposes such as paring, cutting or slicing vegetables and fruit; ripping seams in garments; sharpening pencils; cutting paper; erasing ink; scraping and removing paint from wood and other surfaces, etc. Other objects and advantages will appear as the invention is hereinafter disclosed.

Referring to the drawings which disclose what I now consider preferred forms of the invention:—

Fig. 1 is a side view of one form of used blade holder illustrating the use of a used blade of the "Durham Duplex" type, one part of the holder being shown in section.

Fig. 2 is a view of the opposite side of the holder shown in Fig. 1 and showing a blade of the "Gillette" type mounted therein.

Fig. 3 is a view similar to Fig. 2, but partly in section and illustrating a slight modification and also a blade of the "Ever Ready" type mounted in the holder.

Fig. 4 is a view of the blank from which the body portion of the holder is constructed.

Figs. 5, 6 are sections on the lines 5—5 and 6—6 respectively of Fig. 1.

Fig. 7 is a section on the line 7—7 of Fig. 3.

The holder, illustrated in the drawings, comprises a body portion and a member which telescopes therewith to form a smooth gripping portion and to hold the razor blade or blades in position. The body portion 10 may be constructed from the blank shown in Fig. 4 by placing a reinforcing rod or strip 11 along the center line and then bending the blank up around this rod. The flaps 12 and 13 will then assume the positions shown in Figs. 1 to 3. It will be noted that the blank is slit at 14 and cut away at 15 and the purpose of these features will

appear hereinafter. The small end flaps 16 are bent (on the dotted lines shown in Fig. 4) around to lie flat against the exterior of the flap 13 as shown in Fig. 1. That part 70 of the body portion 10 which lies between the slit 14 and the nearest end of the body portion is formed to receive a blade 17 of the "Durham duplex" type. Fig. 5 clearly shows the blade-receiving pocket last referred to. In order to hold the blade 17 securely in position and to provide a smooth gripping portion, a member 18 is provided. This member is U-shaped in cross-section and provided with a slit extending from 75 the point 19 to the nearest end of said member 18 to receive the blade 17 when the parts 10 and 18 are assembled as shown in Fig. 1. It will be seen that the operator may grip the lower portion of the now complete holder and use the implement in the same manner as a paring knife is employed.

Or, the device may be utilized for other purposes some of which have been above enumerated. The parts 10, 17 and 18 are 80 easy to assemble. A blade 17 is simply slipped into position between the side flaps 12 and 13 of the body portion 10, the member 18 is telescoped over the edge of the body portion and slid endwise until the blade 17 is forced against the inner wall of the curved end 20. The blade is then 85 securely held in position by virtue of the curvature of the end 20 and the shoulder at 19 on the member 18. The operation to 90 reverse a blade or to substitute a different blade will be apparent to those skilled in 95 100

the art in view of the foregoing disclosure. Razor blades of other types may be mounted in the upper end of the holder. For example blades of the "Gillette" type may 5 be employed, as indicated in Fig. 2 at 17^a.

A preferred construction of the mid portion of the holder is indicated in Figs. 1 and 6. That portion of the flap 13 which lies between the slit 14 and cut-away portion 15 is in quite close contact with the 10 opposite flap 12, especially at its outer edge. Furthermore the flap 12 is preferably cut away as indicated at 21 to accommodate a modified form of member 18, more specifically described in connection with Fig. 3.

The opposite end of the holder is especially designed to receive and hold a razor blade 23 of the "Ever Ready" type, i. e. a blade provided with a backing or reinforcing strip 22. As shown more clearly in 20 Fig. 7 the parts of flaps 12 and 13 which lie between the cut out portion 15 and the end 24 of the holder are so shaped as to provide a pocket 25 to receive and grip the strip 22, the flaps being bent in at more 25 nearly to grip the blade portion 23. The blade 23 may be mounted in the body portion of the holder by inserting one end of the strip 22 into the cut-out 15 and then 30 forcing it endwise between the flaps 12 and 13 until it assumes the position shown in Fig. 3. The member 18 may then be placed in position with its slit receiving the blade.

The invention is susceptible to modification 35 in various respects. For example instead of employing a member 18 of the design shown in Figs. 1 and 2, a member such as the one illustrated in Fig. 3 may be utilized. This member 26 is also U-shaped in 40 cross-section but is slit at both ends, i. e. from the point 27 to the adjacent end and 45 from the point 28 to the end adjacent the latter. The member 26 is shown curved in at 29 to conform to the curvature of the edge portion 21 (see Fig. 1) and to form an effective grip for the hand, when the operator prefers a short grip on the implement.

The flaps 12 and 13 are preferably so 50 biased toward each other that, by virtue of the inherent resiliency of the metal of which they are composed, they exert a frictional gripping pressure on the blades 17, 17^a and 23.

It will be appreciated that I have provided a useful, effective though inexpensive device for using old, formerly discarded 55 razor blades for any of the purposes above set forth.

In accordance with the provisions of the 60 patent statutes, I have herein described the principle of operation of my invention, together with the apparatus which I now consider to represent the best embodiments 65 thereof, but I desire to have it understood

that the apparatus disclosed is only illustrative and that the invention can be carried out by other means. Also while it is designed to use the various features and elements in the combinations and relations described, some of these may be altered and others omitted and certain of the features of each modification may be embodied in the others without interfering with the more general results and effects outlined, 70 and the invention extends to such use.

What I claim is:—

1. A holder for razor blades comprising in combination, a body portion which is substantially U-shaped in cross-section to 80 form a pocket into which a razor blade may be inserted and from which a razor blade may be readily removed, said pocket being of such depth that a sharp edge of a blade mounted therein projects beyond the open 85 side of the U-shaped section, an abutment on said body portion against which the outer end of a blade mounted in said pocket engages, and means comprising a member substantially U-shaped in cross-section and adapted to receive and telescope with said body portion to hold the outer end of a blade against said abutment with a sharp edge of the blade exposed for use.

2. A holder for razor blades comprising 95 in combination, a body portion which is substantially U-shaped in cross section and adapted to receive a blade, and a member also substantially U-shaped in cross section and adapted to telescope with the body portion 100 to form a handle, said body portion and member being provided with coacting means to engage the opposite ends of a blade to hold the blade between said body portion and member with the blade edge 105 in exposed position.

3. A holder for razor blades comprising in combination, a body portion having a blade-receiving pocket closed at one end, and means comprising a detachable member substantially U-shaped in cross section adapted to receive and telescope with said body portion for holding a blade between the closed end of said pocket and said member with a sharp edge of the blade exposed 115 for use.

4. A holder for razor blades comprising in combination, a body portion which is substantially U-shaped in cross-section to 120 form a pocket into which a razor blade may be inserted and from which a razor blade may be readily removed, said pocket being of such depth that a sharp edge of a blade mounted therein projects beyond the open side of the U-shaped section, an abutment on said body portion against which the outer end of a blade mounted in said pocket engages, and means comprising a member substantially U-shaped in cross-section adapted 125 to receive and telescope with said body portion to hold the outer end of a blade against said abutment with a sharp edge of the blade exposed 130 for use.

tion and to engage the inner end of a blade to hold the outer end thereof against said abutment with a sharp edge of the blade exposed for use, said U-shaped body portion and U-shaped member cooperating to form the handle of a knife of which the exposed edge of the blade constitutes the cutting portion, the opposite edges of the handle

consisting of the rounded edges of the U-shaped body portion and U-shaped member.

In testimony whereof I hereto affix my signature.

MURIEL BURKE-HENNESSY.

Witness:

NATHAN NEWMAN.
